DUAL MAGNETRON AND CIRCUITS

Jan Forman, Malvern, Pa., assignor to Burroughs Corporation, Detroit, Mich., a corporation of Michigan

Application March 15, 1956, Serial No. 571,781

7 Claims. (Cl. 331—86)

This invention relates to electronic tubes and more particularly relates to a compound magnetron tube in a coaxial arrangement and circuits therefor.

The electronic behavior of cylindrical magnetrons is well known, as published by A. W. Hull in Physical Review, vol. 18, p. 31, of 1921, and as shown and described in United States Patent No. 2,099,300 issued to K. Fritz entitled "Oscillation Generator." With an elongated cathode, a coaxial, cylindrical anode structure and a magnetic field whose flux lines permeate the tube parallel to the cathode, these tubes will oscillate in various modes depending upon the strengths of applied magnetic and electrical fields. Some modes have high-intensity oscillations while others are quite feeble. If a split-anode type magnetron is used and a resonant circuit is connected between anode segments of such a tube and the proper interelectrode voltage is applied in relation to the magnetic field permeating the tube, the tube will oscillate due to a negative resistance characteristic between its elements. In the production of these oscillations, electrons emitted from the cathode are accelerated to high kinetic energy and bombard the anode. Their kinetic energy is changed to heat when the electrons strike the anode, and the anode can be raised to high temperatures through such heating, with considerable efficiency in the energy conversion.

In most vacuum tubes, anode heating due to electron bombardment serves no good purpose, but rather contributes to lowered operating efficiency and shortened tube life.

An object of this invention is to provide a novel cathode structure for all tubes requiring axial magnetic fields and novel circuit arrangements for such tubes.

Another object of this invention is to utilize a magnetron oscillator to provide heat for the thermionic cathode of a surrounding magnetron device and simultaneously to provide alternating voltages useful in associated apparatus.

Another object of this invention is to utilize a magnetron tube oscillator to provide heat for a thermionic cathode and alternating voltage for simultaneous power supply and switching signals of a coaxial magnetron beam switching tube.

Yet another object of this invention is to utilize a magnetron tube oscillator to provide heat for a thermionic cathode of a surrounding magnetron tube and simultaneously alternating voltages which may be synchronized with an applied signal to provide a useful output signal at that frequency.

Still another object of this invention is to utilize oscillations of an inner magnetron to provide heat for the thermionic cathode of an outer, surrounding magnetron and simultaneously to provide alternating voltages useful in the associated apparatus or for radiation, and wherein the surrounding magnetron oscillates at an independent frequency or at a harmonically related frequency, to provide complex waveforms in the mixture of their respective outputs.

2

In accordance with this invention a first, cylindrical anode magnetron is positioned in the center of a second, multiple-anode magnetron, with the outer surface of the cylindrical anode providing an emitting surface and a separate electron stream for the multiple anode magnetron, with a single magnet providing the magnetic flux for both magnetrons; and wherein the resonant circuits connected to the first anode are used in accordance with one phase of the invention to supply various operating voltages for the second magnetron.

For a more detailed description of this invention, reference is made to the drawings in which:

Fig. 1A is a schematic circuit diagram of a dual magnetron and associated circuitry embodying the invention;

Fig. 1B is a schematic diagram of typical circuit connections to each spade and target electrode of a magnetron beam switching tube;

Fig. 1C is a schematic diagram of a continuous cylinder magnetron oscillator useful as the inner magnetron;

Fig. 2A is a schematic diagram of an embodiment of the invention for producing operating voltages from the output circuit of the inner magnetron of the dual magnetron;

Fig. 2B is a schematic diagram of a circuit utilizing the inner magnetron's oscillations for radio transmission;

Fig. 3 is a schematic diagram of output circuits for a four-element split anode inner magnetron;

Fig. 4 is a schematic diagram of an output circuit connected for synchronization with an external signal; and

Fig. 5 is a schematic diagram of a further synchronizing circuit embodiment of the invention.

As shown in Fig. 1A, evacuated envelope 20 contains a dual magnetron. Targets 21, spades 22 and switching grids 23 are arranged to form the succession of beam forming and holding positions of a magnetron beam switching tube. This arrangement of outer electrodes is described in detail in United States Patent No. 2,721,955 to Sin-pih Fan et al., entitled "Multi-Position Beam Tube." Other configurations of outer anode structure could be used within the scope of one phase of this invention. Split anodes, and cavity resonators in a metallic block, as shown for anode structure 28 in Fig. 4, are typical examples of alternate outer anode structures.

A cylindrical cathode 24 is provided for operation with the above described electrodes 21, 22 and 23. Cylinder 24 is of comparatively large diameter, and may be continuous, as shown in Fig. 1C, or split axially into a plurality of segments, as in Fig. 1A where cylinder 24 is shown split into segments 25 and 26.

While the outer surface of cylinder 24 is a cathode for one magnetron structure, the inner surface of this cylinder is the anode for a second magnetron structure, coaxial to the first. Cathode 27 is a tube positioned on the axis of cylinder 24, with a heater therein to raise it to electron emissive temperature. Electrons from cathode 27 can get no further than cylinder 24 because the gaps between segments 25 and 26 are exceedingly small and do not allow electrons to pass.

For magnetron type operation, a magnetic field permeates the dual tube structure, with flux lines substantially parallel to the axis thereof. This field is represented by the head-on view of flux arrow H in Fig. 1A. Also, a positive voltage is applied to all targets 21 and spades 22 through resistors 31 and 32 respectively as shown in Fig. 1B. Ground connection 33 on the center tap of coil 35 keeps cylinder 24 at ground potential relative to targets 21 and spades 22, to function as a cathode when heated to electron emissive temperature.

As shown in Fig. 1C, the inner magnetron may be of the continuous cylinder anode type with oscillations between cathode and anode. However, the preferred embodiment is the split anode magnetron.

A voltage source such as battery 34 is connected between cathode 27 and segments 25 and 26 of cylinder 24, to put cylinder 24 at a positive voltage relative to cathode 27. With cathode 27 heated to electron emissive temperature, and with battery 34 providing a cathode-to-anode voltage suitable for magnetron oscillation, this inner magnetron structure will transfer oscillatory energy to a connected resonant circuit such as the resonator comprising coil 35 and capacitor 36. Other forms of resonator also can be used with the inner magnetron, such as cavities within a thickened cylinder 24, Lecher wires, etc. For split-anode type oscillators, the magnetron presents a negative resistance across this tuned circuit, of a magnitude adequate for overcoming the positive resistance of the tuned circuit and of other circuits coupled to it. As electrons move from cathode 27 to anode cylinder 24, they acquire kinetic energy. This energy is transformed to heat when the electrons strike cylinder 24, and the total electron flow in this inner diode heats cylinder 24 to such high temperatures that the outer surfaces of segments 25 and 26 become electron emissive. The inner surface of cylinder 24 cannot contribute to this emission since the cylinder encloses its own inner surface. If desired, these outer surfaces can be coated with suitable electron emitters which provide more electron emission at lower temperatures than plain metallic surfaces would provide.

Being electron emissive, the outer surface of cylinder 24 serves as a cathode for the outer magnetron. When the outer magnetron device is a magnetron beam switching tube, the relationship between supply voltage $+E$ on the targets and spades with respect to the cylinder 24 and the magnetic field H through the tube must be such as to put the outer magnetron device well into its magnetron cut-off region. In general, the supply voltages to the outer magnetron device must be such that, in conjunction with the magnetic field required by the inner magnetron, the outer magnetron may be operated satisfactorily. Operation of this outer magnetron, when it is a magnetron beam switching tube, is as described in the above cited patent. No beam will form while the tube is in magnetron cut-off condition as described, until the potential on one of the spade electrodes 22 is depressed to about half the normal spade voltage. Then, the electrons which have been orbiting around the cathode cylinder 24 but never reaching the spades 22 or targets 21 will be confronted by a negative voltage barrier in the cathode-to-spade area nearest to the lower voltage spade. The electrons are diverted by this barrier, tending to flow along an equipotential line which leads then in between two spades to strike the target which covers this inter-spade space. This beam path grazes the lower-voltage spade, and some beam current flows to that spade. This current produces enough IR voltage drop through the resistor connecting the spade to its voltage supply $+E$ to hold the spade's voltage down to where the beam is held stably in that position.

A switching grid 23 also is in the beam holding cavity defined by the lower-voltage spade, the next spade and the target covering the gap between these spades. If this grid 23 is lowered in voltage below its bias $+V_g$, a voltage is reached at which the beam fans out toward this switching grid 23 and begins to strike the next spade, depressing it in voltage from $+E$ and causing the beam to advance to the next stable position where it is held as described for the former position. With successive switching grids driven toward a negative voltage in the proper sequence, the beam will continue to advance from one beam holding position to the next.

A suitable grid switching circuit is provided by common connections of alternate grids which are driven through a push-pull or balanced circuit, as shown in Fig. 1A. When one set of alternate grids is driven in the negative direction and causes the beam to switch, the other set of alternate grids, which includes the grid in

the position to which the beam is switching, is driven more positive so that the beam's switching advances only one position in that half-cycle of the switching signal. On the next half-cycle, another single position advance is made.

The previously described oscillations of the inner magnetron produces an alternating current in coil 35. Coil 37 is coupled magnetically to coil 35 and is connected through ring connectors 38 and 39 to sets of alternate grids 23. The center tap on coil 37 is biased by voltage $+V_g$ for proper switching and beam holding in tube 20. This coupling provides the alternating voltage needed for the above-described switching sequence of the outer magnetron's beam.

Fig. 2A shows a different circuit including secondary winding 40 coupled to coil 35 of the resonant circuit for the inner magnetron oscillator. Rectifiers 41 and 42 are connected to provide a full wave rectifier, developing a direct voltage from the center tap of coil 40 to the anodes of rectifiers 41 and 42. This voltage can be used to energize the spades and targets of the outer magnetron by adding lead 45 for cathode connection and connecting lead 46 of Fig. 1B to the positive terminal 47. Both secondary circuit 37 of Fig. 1A and 40 of Fig. 2A could be coupled to the resonant circuit of one oscillator, thus providing in one component both the spade and anode voltage supply and the switching signal.

Fig. 2B shows another use for the alternating voltage provided by the inner magnetron. When this magnetron is tuned to provide a high frequency, the alternating voltage can be used as a radio carrier on antenna 30.

Fig. 3 shows a variation wherein cylinder 24 is split into four segments 50, 51, 52 and 53. One pair of segments 50 and 53 energize resonant circuit 54, to which is coupled coil 55 to provide the switching signals on grids 23 of an outer magnetron as shown in Fig. 1. The other pair of segments 51 and 52 energize resonant circuit 56, to which is coupled coil 57. Coil 57 applies voltage to diodes 58 and 59 forming a full-wave rectifier. Capacitor 60 filters the oscillator frequency out of the rectified output. Further filtering circuits may be used if desired, but a simple capacitor provides adequate filtering when the frequency is a radio frequency, due to its very low reactance to high frequency. This direct current output can be connected to the supply lead for all spades and targets, as described for Fig. 2. This inner magnetron is energized by battery 34 and a heater for cathode 27 and oscillates as previously described. Resonant circuits 54 and 56 must be tuned to the same frequency to enable oscillations in the illustrated circuit.

In Fig. 3, the anode heating again is utilized to raise the outer surfaces of segments 50, 51, 52 and 53 to electron emissive temperature, as a cathode for an outer magnetron. Also, resonant circuits 54 and 56 could be connected to opposite segments, rather than to adjacent segments as shown, and function as an oscillator with equal or improved quality of performance.

Fig. 4 shows a four segment split anode magnetron in which any pair of anode segments supply a signal which can be utilized for any purpose, and the remaining two segments are fed with a locking signal at a frequency to which the magnetron's oscillations are to be synchronized. Resistor 61 is loading the resonant circuit 62 so as to broaden its response for ease of synchronizing through a small band of frequencies within which the magnetron is tuned to oscillate in any event. The anode heating is used to provide a cathode for an outer magnetron as previously described.

Fig. 5 shows another synchronized magnetron oscillator, except that grid wires 63 and 64 parallel to the axis receive the synchronizing voltage and split anode segments 65 and 66 are coupled to resonant circuit 62. Oscillations of this inner magnetron are synchronized by incoming signals on input transformer 67 applied to grid wires 63 and 64, and the resultant anode heating enables

segments 65 and 66 to function as cathodes for an outer magnetron.

While coil-capacitor resonant circuits have been shown, other components such as Lecher Wires, tuned coaxial-line sections, cavity resonators or ferro-magnetic-cored inductances with suitable capacities also could be used. For ultra-high frequencies and microwaves, the resonant circuits can be within the tube envelope or be part of the envelope as in metal-ceramic tubes.

In Figs. 2, 3, 4 and 5 the collector and other electrodes of the outer magnetron are omitted in order to more clearly show and describe the inner magnetron, its circuitry, and use of its heating function to provide a cathode for the outer magnetron and of its oscillations to provide switching signals and D.C. supply for the outer magnetron.

What is claimed is:

1. A magnetron tube circuit including a magnetron tube comprising an anode structure, a first cathode coaxial to said anode structure, a plurality of electrodes parallel to and positioned concentrically around said cathode, the inner surface of said electrodes providing anodes for said first cathode and the outer surface thereof of providing a cathode assembly for said anode structure, and at least one resonant circuit connected to separate electrodes of said plurality of electrodes to tune the oscillations between separate electrodes of said plurality of electrodes and to provide a useful alternating output voltage.

2. A coaxial dual magnetron beam switching circuit comprising a central cathode, a multiple segment cylindrical anode concentric about said cathode, a resonant circuit connected to a pair of said segments, a voltage supply connected to said resonant circuit and to said cathode to accelerate electrons from said cathode to said cylindrical anode, an output circuit coupled to said resonant circuit, a cathode surface on the outer surface of said multiple segment cylindrical anode, a circular array of spade electrodes concentric about said cathode surface, a circular array of target electrodes outside of said spade electrodes and covering the gap between successive spade electrodes, and switching grids on a circular locus intermediate between said spade and target electrodes and aligned with one edge of each spade electrode.

3. A coaxial dual magnetron beam switching circuit comprising a central cathode, a multiple segment cylindrical anode concentric about said cathode, a resonant circuit connected to a pair of said segments to establish an oscillatory voltage between segments of said cylindrical anode, a voltage supply connected to said resonant circuit and to said cathode to accelerate electrons from said cathode to said cylindrical anode, an output circuit coupled to said resonant circuit, a cathode surface on the outer surface of said multiple segment cylindrical anode, a circular array of spade electrodes concentric about said cathode surface, a circular array of target electrodes outside of said spade electrodes and covering the gap between successive spade electrodes, switching grids on a circular locus intermediate between said spade and target electrodes and aligned with one edge of each spade electrode, and circuit means connecting said switching grids in common connections of alternate grids and to said output circuit to utilize said oscillatory voltages to cause switching action for a beam in said circular arrays.

4. A coaxial dual magnetron beam switching circuit comprising a central cathode, a multiple segment cylind-

rical anode concentric about said cathode, a first resonant circuit connected to a first pair of said segments, a second resonant circuit connected to a second pair of said segments, a voltage supply connected to said resonant circuits and to said cathode to accelerate electrons from said cathode to said cylindrical anode, output circuits coupled to said resonant circuits, a cathode surface on the outer surface of said multiple segment cylindrical anode, a circular array of spade electrodes concentric about said cathode surface, a circular array of target electrodes outside of and concentric to said spade electrodes and positioned along a circular locus to cover the gap between successive spade electrodes, and switching grids on a circular locus intermediate between said spade and target electrodes and aligned with one edge of each spade electrode.

5. A composite magnetron tube and circuit comprising a first magnetron including a central electron-emissive first cathode and a surrounding coaxial electron-receiving anode, and a second magnetron including said electron-receiving anode as a second cathode and having an outer electron-emissive surface, a plurality of electron receiving anodes surrounding and coaxial with said second cathode, means common to said first and second magnetrons for providing a magnetic field therefor, and including a common resonant circuit coupled between said first and second magnetrons.

6. A magnetron circuit including a composite magnetron tube comprising a first magnetron including a central electron-emissive first cathode and a surrounding coaxial electron-receiving anode, a second magnetron including said electron-receiving anode as a second cathode and a plurality of groups of electron-receiving electrodes surrounding and coaxial with said second cathode, said groups of electrodes including switching electrodes, a resonant circuit coupled between said first magnetron and said switching electrodes of said second magnetron, and a magnet surrounding said first and second magnetrons and providing an axial magnetic field therefor.

7. A coaxial dual magnetron beam switching circuit comprising a central cathode, a multiple segment cylindrical anode concentric about said cathode, a resonant circuit connected to a pair of said segments, an output circuit coupled to said resonant circuit, a cathode surface on the outer surface of said multiple segment cylindrical anode, a circular array of spade electrodes concentric about said cathode surface, a circular array of target electrodes behind said spade electrodes and covering the gap between successive spade electrodes, and switching grid electrodes on a circular locus intermediate between said spade and target electrodes with each grid aligned with one edge of a spade electrode.
